BLOWER CASING

Oscar C. Palmer, Phoenix, Ariz., assignor to
 Palmer Manufacturing Corp., Phoenix, Ariz.,
 a corporation of Arizona

Application May 10, 1948, Serial No. 26,150

4 Claims. (Cl. 230—232)

1

This invention relates to air conditioning equipment, and is particularly directed to improvements in evaporative coolers which are used for cooling and humidifying atmospheric air. Evaporative coolers commonly are provided with a fan or blower for drawing air through water saturated pads and directing the air through an outlet opening provided in the shell or casing of the cooler unit.

The principal object of this invention is to provide an improved form of discharge opening for an evaporative cooler.

Another object is to provide a cooler casing having a discharge opening in one wall thereof cooperating in a novel manner with the outlet of a blower housing mounted within the casing of the evaporative cooler unit.

Other and more detailed objects and advantages will appear hereinafter.

In the drawings:

Figure 1 is a perspective view showing an evaporative cooler embodying my invention.

Figure 2 is a partial sectional view taken substantially on the lines 2—2 as shown in Figure 1.

Figure 3 is a sectional detail taken substantially on the lines 3—3 as shown in Figure 1.

Figure 4 is a partial sectional elevation taken substantially on the lines 4—4 as shown in Figure 3.

Referring to the drawings, the casing 10 is generally cubical in construction and includes the usual top 11, bottom 12, sides 13, back 14, and front 15. Evaporative cooler pads 9 are provided on each of the walls 13 and 14, while the top and bottom walls 11 and 12 are substantially imperforate. Covers 16 having multiple apertures 17 may be provided for the walls 13 and 14 if desired. A blower unit generally designated 18 is mounted within the enclosure 19 provided by the casing 10, and the function of this blower is to draw atmospheric air in through the apertures 17 and through water saturated evaporative pads into the enclosure 19 and then to blow it outwardly through the discharge opening 20 provided in the front wall 15 of the casing 10. This blower unit 18 may include a frame 21 mounted on rubber bushings 22 attached to the bottom wall 12. A blower housing 23 which may be of general involute shape is provided with upper and lower walls 24 and 25 and side walls 26 which cooperate to define the outlet end 27 of the blower unit.

A rotor 46 is provided with the usual blades 28 and is mounted on a rotary shaft 29 supported on pillow blocks 30. The pillow blocks 30 are bolted or otherwise secured to the frame 21. A pulley 55

2

31 fixed to the shaft 29 is adapted to be driven from an electric motor 32 by means of a belt 33. Rotation of the pulley 31 by means of the motor 32 serves to cause rotation of the blower in the direction indicated by the arrow 34 and thus draw air in laterally through the side openings 35 in the side walls 26, and expel the air outwardly through the outlet end of the blower unit.

In accordance with my invention the front wall

10 15 is provided with an integral protrusion 36 extending forwardly of the plane defined by the front wall to enclose the outlet end of the blower unit 18. This protrusion 36 has a front face 37 disposed in a plane parallel to the plane of the

15 wall 15 and is provided with an integral re-entrant flange 38 extending rearwardly into the outlet end 27 of the blower unit and conforming to the shape thereto. The protrusion 36 and re-entrant flange 38 are preferably formed from the

20 same flat sheet of material as the front wall 15 and is preferably accomplished by means of stamping operations. As shown in the drawings, the protrusion 36 and re-entrant flange 38 co-

25 operate to provide continuous recess 39 into which the outlet end 27 of the blower unit 18 projects. A continuous rubber-like gasket 40 is positioned between the flange 38 and the walls of the blower unit forming the outlet end 27 in order to form a seal therebetween. As shown in the drawings, this rubber-like gasket 40 may be mounted on the outlet end 27 of the blower unit and adapted to contact the flange 38.

30 Vertically extending direction controlling vanes 41 may be mounted within the space bounded by the continuous flange 38. These vanes 41 may

35 comprise strips having their ends turned at right angle and secured to the flange 38 by means of suitable fastener elements 42. These elements 42 may be adapted to permit the individual vanes 41 to be turned at any desired angle as shown at 40 41a in Figure 3. This construction employing the integral protusion 36 and the re-entrant continuous flange 38 reduces the number of forming operations, simplifies the design, and eliminates a number of parts employed in conventional

45 evaporative coolers. The re-entrant flange 38 also provides a highly advantageous support for the outlet end of the blower unit 18, thereby contributing to the supporting connection between the blower unit 18 and the casing 10.

50 The front face 37 of the protusion 36 forms a convenient control panel for regulating the operation of the evaporative cooler. The knob 43 may be adapted to operate the control switch (not shown) for the motor 32, and the knob 44 may be

connected to control the flow of water to the evaporative pads. The center knob 45 may comprise a temperature and humidity indicating dial if desired and may be provided with a suitable mounting for the name plate emblem. The electrical connections associated with the knob 43 as well as the piping associated with the knob 44 have been omitted in the drawing for clarity of illustration, since these constructional details are well understood in the art and form no part of my present invention.

Having fully described my invention, it is to be understood that I do not wish to be limited to the details herein set forth, but my invention is of the full scope of the appended claims.

I claim:

1. In a blower installation, the combination of walls defining a chamber, and a blower unit positioned within the chamber, said blower unit having forwardly directed walls defining an outlet end, one of the walls forming the chamber having an integral protusion extending forwardly therefrom and having an integral reentrant flange extending in telescopic relation with respect to the outlet end of the blower unit, the outlet end of the blower unit being supported by said reentrant flange with the load of said outlet end being applied to said flange in an area disposed exteriorly of the plane of the latter of said walls.

2. In a blower installation, the combination of walls defining a chamber, a blower unit positioned within the chamber, said blower unit having forwardly directed walls defining an outlet end, one of the walls forming the chamber having an integral protusion extending forwardly therefrom and having an integral reentrant flange extending in telescopic relation with respect to the outlet end of the blower unit, the outlet end of the blower unit being supported by said reentrant flange with the load of said outlet end being applied to said flange in an area disposed exteriorly of the plane of the latter of said walls, and a continuous rubber-like gasket interposed between the outlet of the blower unit and said flange.

3. In a blower installation having walls defining a chamber, one of the walls having a discharge opening provided therein through which air may be expelled from the chamber; a combination of

a blower unit mounted within the chamber and having an outlet end for discharging air through the discharge opening, the discharge opening in said wall being formed by an integral protusion extending forwardly from said wall and having a reentrant flange cooperating with the protusion to define a continuous recess, the recess being adapted to receive the extending outlet end of the blower unit, the outlet end of the blower unit being supported by said integral reentrant flange with the load of said outlet end being applied to said flange in an area disposed exteriorly of the plane of the latter of said walls.

4. In a blower installation having walls defining a chamber, one of the walls having a discharge opening provided therein through which air may be expelled from the chamber; a combination of a blower unit mounted within the chamber and having an outlet end for discharging air through the discharge opening, the discharge opening in said wall being formed by an integral protusion extending forwardly from said wall and having a reentrant flange cooperating with the protusion to define a continuous recess, the recess being adapted to receive the extending outlet end of the blower unit, the outlet end of the blower unit being supported by said integral reentrant flange with the load of said outlet end being applied to said flange in an area disposed exteriorly of the plane of the latter of said walls; and a resilient gasket interposed between the outlet end of the blower unit and said flange and adapted to form a seal therebetween.

OSCAR C. PALMER.
